UNITED STATES PATENT OFFICE

ALBERT F. BREITENSTEIN, OF NEW HAVEN, CONNECTICUT, ASSIGNOR TO THE
GEOMETRIC TOOL COMPANY, OF NEW HAVEN, CONNECTICUT, A CORPORATION

SELF-OPENING DIE-HEAD

Application filed May 2, 1930. Serial No. 449,233.

This invention relates to an improvement in self-opening die-heads and particularly to an improvement in that class of self-opening die-heads in which the chasers are mounted in a chaser-carrying member which is mounted, in turn, with capacity for independent reciprocating movement in a mounting-member designed to be secured in the turret or other appropriate feature of a machine.

Heretofore, it has been an extremely difficult operation to cut threads of fine pitch and of delicate form on a so-called "production basis" without occasioning a large amount of spoilage due to the tendency of the chasers to "strip" such relatively-delicate threads.

The main object of this invention is to produce a convenient and reliable self-opening die-head constructed with particular reference to the sensitiveness of its tripping mechanism, whereby threads of fine pitch and delicate form may be rapidly and accurately cut without danger of stripping.

With the above and other objects in view as will appear from the following, my invention consists in a self-opening die-head of the type which is automatically tripped for the retirement of its chasers by the forward draft exerted by the work upon a floating chaser-carrying member, and characterized by having means engageable with an external abutment for imparting relative forward motion to the said floating chaser-carrying member for releasing the said chasers, whereby the tool may be tripped either by the forward draft exerted by the work or by the said means, to adapt the tool for use in work in which the threads cut are too delicate to withstand the pull required to release the chasers.

My invention further consists in a self-opening die-head characterized as above and having certain other details of construction and combinations of parts as will be herein-after described and particularly recited in the claim.

In the accompanying drawings:

Fig. 1 is a view in side elevation of a self-

opening die-head embodying my invention;

Fig. 2 is a view of the rear end thereof;

Fig. 3 is a view thereof in front elevation;

Fig. 4 is a view thereof in vertical central longitudinal section, with the parts in the 55 positions due to them when the chasers are in their cutting positions;

Fig. 5 is a similar view with the parts thereof in the positions due to them when the die-head is about to open;

Fig. 6 is a similar view with the parts thereof in the positions due to them when the chasers have been automatically retired out of engagement with the work;

Fig. 7 is a broken longitudinal sectional 65 view taken on the line 7-7 of Fig. 3;

Fig. 8 is a corresponding view taken on the line 8-8 of Fig. 3;

Fig. 9 is a corresponding view taken on the line 9-9 of Fig. 3;

Fig. 10 is a view in side elevation of the mounting-member detached;

Fig. 11 is a view thereof in rear elevation; and

Fig. 12 is a detached perspective view of 75 the tripping-lever.

In the embodiment of my invention herein chosen for illustration, I employ a mounting-member 20, a chaser-carrying member 21, a sleeve-like chaser-operating member 22, 80 and a locking-member 23. The said mounting-member 20 has a hollow shank 24, by means of which the fixture is mounted in a turret 25, or other appropriate feature, of any machine suitable for threading operations. 85

At its forward end, the said mounting-member 20 is provided with a concentric bore 26 for the sliding reception of the hollow shank 27 of the chaser-carrying member 21, the forward face of which latter is provided 90 with four radially-arranged slots 28 receiving radially-movable chasers 29 having their inner ends formed with cutting-teeth 30, and their outer ends provided with bevels 31 for co-action with beveled notches 32 located 95 within the forward end of the sleeve-like chaser-operating member 22, which is slidably mounted upon the forward end of the chaser-carrying member 21.

Each of the chasers 29 is provided, near its 100

outer end, with a rearwardly-extending pin 33, engaged by a plunger 34 normally urged outward by a spring 35, the said plunger and spring being located in a radial bore 36 formed in the chaser-carrying member 21, and 5 intercommunicating with the radial slots 28 aforesaid.

At its rear end, the sleeve-like chaser-operating member 22 is internally-threaded for the reception of the externally-threaded tubular forward end of an adjusting-ring 37, 10 virtually forming a part of the said chaser-operating member and sliding upon the periphery of the mounting-member 20, the flanged rear end of the said ring being provided with radial wrench-sockets 38 for the 15 application of an ordinary spanner wrench, by means of which the ring is turned inward or outward as desired, with respect to the operating-member 22, so as to change the position of the beveled notches 32 therein, with 20 respect to the locking-member 23, whereby the diameter of the threads cut by the chasers may be varied.

The forward face of the flanged rear end of 25 the adjusting-ring 37 is provided with an annular series of circular shallow seats or depressions 39, with any one of which a friction-plunger 40 is normally engaged for preventing the accidental rotation of the ring 37 with respect to the chaser-operating member 22, which latter is formed with a bore 41 for 30 the reception of the said plunger 40, and also for the reception of the spring 42 by means of 35 which the same is urged into engagement with any given one of the series of seats 39.

For preventing the relative rotation of the chaser-carrying member 21 with respect to the chaser-operating member 22 without interfering with their relative rectilinear movement, I employ two locking-pins 43 driven 40 into and projecting forward from an annular bearing-rib 44 formed within the chaser-operating member 22 and entering passages 45 in the chaser-carrier, as shown in Fig. 8.

To provide for moving the chaser-operating member 22 rearward with respect to the chaser-carrying member 21 for the purpose of permitting the chasers to move into their 50 open positions under the urge of their springs 35, I employ two springs 46 located diametrically opposite each other in registered bores 47 and 48, respectively formed in the said members 21 and 22, as shown in Fig. 9. Each 55 spring 46 encircles a guide-pin 49 mounted in the chaser-carrying member 21 and extending rearward therefrom through its bore 47 and partway into the aligned bore 48 in the chaser-operating member 22.

For locking the chaser-operating member 22 in its forward chaser-closing position, as 60 shown in Fig. 4, against the counter-urge of the springs 46, just described, I employ the segmental locking-member 23 before mentioned which is located in a forwardly- and

inwardly-inclined substantially semi-circular slot 50 formed in the mounting-member 20. This locking-member is formed at its rear end with a segmental external locking-rib 51, the forward edge of which co-acts with 70 the forward wall of a shallow circumferential internal locking-groove 52 formed in the adjusting-ring 37.

Near its forward end the locking-member 23 is formed with a segmental internal coupling-rib 53 entering a corresponding coupling-groove 54 formed in the shank 27 of the chaser-carrying member 21 whereby the said locking-member participates in the reciprocating movement of the said chaser-carrying member as will hereinafter appear.

In order to disengage the forward edge of its locking-rib 51 from the forward wall of the internal groove 52, the locking-member 23 before referred to is concurrently moved inward as well as forward by its provision with a bevel 55 forming its forward face and riding upon the forward wall 56 of the inclined slot 50 in the mounting-member 20.

For re-locking the fixture with the chasers 90 in their inward or cutting positions, the locking-member 23 is concurrently moved rearward and outward for the re-entrance of its locking-rib 51 into the groove 52 when the chaser-carrying member 21 is moved rearward with respect to the mounting-member 20, as will hereinafter appear. For this purpose, the said locking-member is formed with a beveled rear face 57 co-acting with the rear wall 58 of the inclined slot 50.

For effecting the forward movement of the chaser-operating sleeve 22 and the concurrent rearward movement of the chaser-carrying member 21 with respect to the mounting-member 20 and for the purpose of moving the chasers 29 inward into their cutting positions and concurrently re-entering the locking-rib 51 of the locking-member 23 into the locking-groove 52, I employ a resetting-handle 59 rocking on a pin 60 located in a clearance-passage 61 in the chaser-operating member 22, the spherically-contoured inner end 62 of the said lever passing through a clearance-passage 63 in the mounting-member 20 and into a socket 64 in the shank 27 of the chaser-carrying member 21.

For limiting the chaser-opening movement of the chaser-operating member 22, I employ a plunger 65 mounted in a bushing 66 screwed into the periphery of the chaser-operating member 22 and at its inner end entering an elongated recess 67 formed in the periphery of the mounting-member 20 and having at its rear end a hardened abutment-pin 68 against which the inner end of the plunger 65 impinges. The said plunger is normally held in the recess 67 by a spring 69 located within the bushing 66.

For the retraction of the plunger 65 from the recess 67 to permit the operating-member

to move into its chaser-clearance position, it is provided with a knurled finger-button 70.

Under the construction and arrangement of parts above described, it will be seen that the chaser-carrying member 21 and the chaser-operating member 22 have capacity for relative rectilinear movement with respect to each other as well as with respect to the mounting-member 20, this being one of the characteristic features of my improved self-opening die-head.

Coming now to the salient feature of my invention, I employ a tripping-dog or lever 71 hung upon a transverse pivot-pin 72 in a radial clearance-passage 73 formed in the mounting-member 20 at the junction point of the body-portion proper thereof and its hollow shank 24, as clearly shown in Figs. 4 to 6 inclusive. The pivotal dog 71 is provided with a relatively-long outwardly-projecting tail 74 adapted to engage with a suitable abutment such as 75, forming a feature of the machine in which my improved die-head is used.

The opposite or inner end of the dog 71 is formed with a nose 76 engaging the rear end of a thrust-transmitting member in the form of a pin 77 arranged parallel with the axis of the die-head and driven into a socket 78 rearwardly opening from the rear end of the hollow shank 27 of the chaser-carrying member 21. The said thrust-pin 77, for all purposes of function, forms an integral part of the shank 27 of the chaser-carrying member 21 and extends rearward through a clearance-bore 79 in the mounting-member 20 between the concentric-bore 26 thereof and the radial clearance-passage 73 thereof.

In the use of my improved die-head, the work represented by the broken lines 80 in Figs. 4 to 6 inclusive, is rotated in the usual manner while the die-head is bodily moved toward the work on the axial line thereof by the turret 25, or by whatever other fixture the die-head may be mounted in, the die-head being at this time reset and locked with the chasers 29 in their cutting positions, as shown in Fig. 4.

The cutting edges of the chasers now engage with the work 80 and begin the cutting operation during which the die-head is urged axially toward the work with more or less pressure as required. When the desired length of thread has been cut upon the work, the tail 74 of the tripping-dog 71 will have engaged the abutment 75 and been swung into the position in which it is shown in Fig. 5.

The swinging movement of the tripping-dog 71, as just above described, will effect the relative forward axial movement of the chaser-carrying member 21 with respect to the mounting-member 20 and owing to the fact that the locking-member 23 is positively coupled to the said chaser-carrying member 21, it will be moved bodily inward as well

as forward into the position in which it is shown in Fig. 5, in which its locking-rib 51 is all but disengaged from the forward wall of the locking-groove 52 in the adjusting-ring 37.

A slight additional swinging movement of the tripping-dog 71 will effect a slight further relative forward movement of the chaser-carrying member 21 and hence a further inward movement of the locking-member 23 with the effect of entirely disengaging the locking-rib 51 of the latter from the forward edge of the locking-groove 52, thereby releasing the chaser-operating member 22 to the action of its springs 46 which will immediately assert themselves to effect the relative rearward movement of the chaser-operating member independently of the chaser-carrying member and the mounting-member until the plunger 65 strikes the hardened stop-pin 68.

When the chaser-operating member 22 has been moved rearward as described, the chaser-springs 35 will be enabled to assert themselves to move the chasers radially outward and so disengage them from the work 80. The parts will now occupy the positions in which they are shown in Fig. 6 in which the resetting-handle 59 is rearwardly inclined.

The die-head being now disengaged from the work, it is bodily retired and a new piece of work is put in place. The die-head is now reset by swinging the resetting-handle 59 from rear to front, thus effecting the forward axial movement of the chaser-operating sleeve 22 independently of the chaser-carrying member 21 and of the mounting-member 20, whereby the forward wall of the annular locking-groove 52 is moved forward and brought into line with the forward edge of the locking-rib 51 upon the locking-member 23. This phase of the resetting operation moves the parts from the positions in which they are shown in Fig. 6 into the positions in which they are shown in Fig. 5.

Now inasmuch as the shank 27 of the chaser-operating member 22 forms one of the fulera of the resetting-handle 59, the chaser-carrying member 21 will be urged axially rearward at the same time that the operating-member is being moved forward by the handle 59. Therefore, at the instant the forward edge of the locking-rib 51 registers with the forward wall of the locking-groove 52, the chaser-carrying member will move slightly rearward, whereby the locking-member 23 will have its rear face 57 forced against the rear wall 58 of the inclined slot 50 with the effect of positively moving the locking-member outward as well as rearward so as to cause its locking-rib 51 to enter the locking-groove 52. In this last phase, the parts move from the positions in which they are shown in Fig. 5 into the positions in which they are shown in Fig. 4.

The die-head now having been reset, is advanced to the work and the cycle of operation above detailed is repeated.

My improved die-head is also adapted to be tripped independent of the tripping-dog 5 71 in the usual manner of the so-called "pull-off" die-heads, by the action of the work 80 in threading itself into the chasers after the bodily advance of the entire fixture has 10 been halted, all as is well understood in the art and as described in detail in U. S. Patent No. 1,643,832, granted to me September 27, 1927.

I am, of course, aware that tripping-dogs 15 are old in the art of self-opening die-heads, but what I wish to call particular attention to is that the particular tripping-dog shown and described herein acts in a novel manner 20 to move the "floating" chaser-carrying member 21 bodily forward with respect to the mounting-member 20 when a relative rearward force is imposed upon the tail 74 of the said dog.

By employing the novel arrangement of 25 parts just above described, the tripping of the die-head becomes so sensitive that I am enabled to cut threads of fine pitch and delicate form with great rapidity and accuracy without the danger of thread-stripping, 30 which has been a source of constant loss and irritation in the past.

It will be understood by those skilled in the art that my invention may assume varied physical forms without departing from my 35 inventive concept and I, therefore, do not limit myself to the specific embodiment herein chosen for illustration, but only as indicated in the appended claim.

I claim:

40 A self-opening die-head including a mounting-member having a clearance-passage; a floating chaser-carrying member carried by the said mounting-member with capacity for axial movement with respect thereto 45 to and provided with a rearwardly-offsetting thrust-transmitting member entering at its rear end the said clearance-passage in the said mounting-member; chasers installed in the said chaser-carrying member; a chaser-operating member for controlling the said chasers; a locking-member installed in the said mounting-member with capacity for reciprocating movement in a plane inclined with respect to the axis of the die-head and 55 operatively connected to the said chaser-operating member and the said chaser-carrying member for locking the former and being released by a relative forward movement of the latter; a tripping-lever pivotally carried 60 intermediate its ends by the said mounting-member and having one arm extended inwardly into the aforesaid clearance-passage therein and engaging the rear portion of the thrust-transmitting member of the chaser-carrying member and having a complemen-

tary arm extending outwardly away from the die-head structure in position to engage an external abutment.

In testimony whereof, I have signed this specification.

ALBERT F. BREITENSTEIN.
